(57) **CLAIM**

The ornamental design for an adjustable wrench with recessed jaws, as shown and described.

DESCRIPTION

FIG. 1 shows a perspective view of an adjustable wrench with recessed jaws;

FIG. 2 shows a top plan view of the adjustable wrench with recessed jaws;

FIG. 3 shows a bottom plan view of the adjustable wrench with recessed jaws;

FIG. 4 shows a right side view of the adjustable wrench with recessed jaws;

FIG. 5 shows a left side view of the adjustable wrench with recessed jaws;

FIG. 6 shows a front view of the adjustable wrench with recessed jaws; and,

FIG. 7 shows a rear view of the adjustable wrench with recessed jaws.

The shade lines in the Figures show contour and not surface ornamentation.
